UNITED STATES PATENT OFFICE.

MARTIN E. CROW, OF ELKHART, INDIANA.

DESIGN FOR AN AUTOMOBILE-BODY.

51,198.

Specification for Design.

Patented Aug. 28, 1917.

Application filed December 11, 1916. Serial No. 136,375. Term of patent 7 years.

To all whom it may concern:

Be it known that I, MARTIN E. CROW, a citizen of the United States, residing at Elkhart, county of Elkhart, Indiana, have invented a new, original, and ornamental Design for an Automobile-Body, of which the following is a specification, reference being had to the accompanying drawings, forming a part thereof.

In the drawing, Figure 1 is a side eleva-

tion of an automobile body showing my design, and Fig. 2 is a plan view thereof.

I claim:—

The ornamental design for an automobile body, as shown.

MARTIN E. CROW.
